LUMINESCENT TUBE SYSTEM AND APPARATUS

Charles Philippe Boucher, Paterson, and Frederick August Kuhl, Ridgewood, N. J., assignors to Boucher Inventions, Ltd., Washington, D. C., a corporation of Delaware

Application July 14, 1941, Serial No. 403,411

12 Claims. (Cl. 176—124)

Our invention relates to fluorescent tube lighting, and more particularly concerns a new electrical system for such illumination, as well as a new transformer forming part of, and for energizing such system.

One object of our invention, therefore, is to produce a new fluorescent tube lighting system, possessing the advantages of simplicity, small size, small number of parts, compactness and sturdiness, and which at the same time is characterized by its high system power factor, and the minimization of detrimental flicker or stroboscopic effect of the light emission therefrom.

Another object is to produce a high leakage reactance transformer for energizing such electrical system, comprising batteries or banks of two or more tubes, the tube-energizing circuits each requiring a different circuit input, which transformer serves to produce just the required current to energize those tube circuits properly and to maintain proper arc discharge across the respective tubes and to limit the current flow to the rated values.

Other objects and advantages in part will be obvious and in part pointed out hereinafter, in connection with the following description, considered in connection with the accompanying drawing.

Our invention accordingly resides in the several elements and features of construction, and the relation of each of the same to one or more of the others, all as described herein, the scope of the application of which is indicated in the claims at the end of this specification.

In the drawing Figures 1 and 2 comprises side and end elevations, respectively, of a transformer according to our invention, Figure 1 also illustrating the associated system connections according to one embodiment.

Figure 3 depicts in schematic manner, another embodiment of circuit connections, to be associated with the transformer core depicted in Figure 1.

Like reference characters denote like parts throughout the several views of the drawing.

As conducive to a more complete understanding of our invention, it may be noted at this time that the introduction of fluorescent tube lighting into the arts and sciences has been accompanied by the realization that there are certain serious drawbacks and disadvantages in the energizing systems for such tubes which have hitherto been in use. The importance of this comparatively new lighting technique, however, can be appreciated when a moment's considera-

tion is given to the widespread acceptance of this new type of lighting. Not only is the acceptance by the industries, but in the stores and in household lighting, as well. As soon as certain operational problems have been solved, we may safely predict the even more widespread acceptance of fluorescent lighting systems in all fields of illumination.

We confidently attribute the popularity of fluorescent tube lighting to the higher efficiency and hence lower operational costs of such lighting as compared to the old incandescent lamps—their luminous efficiency is about 2½ times as great, so that they cost less than half as much to operate for the same light output; they operate cooler, since not nearly so much current is dissipated in radiant energy; they produce a quieting, soothing light in a variety of color tones and combinations; they produce a more even distribution of light and are admirably adapted, when used in batteries, for flood lighting. Additionally, when used in batteries, such lamps are particularly well suited for color mixing and blending. Because of their comparatively long tube life, about 2½ times those of present day incandescent tubes, the higher first-cost of such systems is more than offset by the lower operational and maintenance costs.

Despite these many advantages attendant upon these new lighting systems, however, much room for improvement awaits the worker in the art. Hitherto, practically all development work has been directed to the use of fluorescent tubes having incandescent electrodes, incandesced to prepare the tube for striking the arc thereacross. Because of these incandescent electrodes the tubes are known as hot cathode tubes. The auxiliary equipment has all been designed for such tubes, with the purpose of both starting them and operating them on service voltages. Because auxiliaries were thought to be necessary in any event for providing starting voltage surge and for current limiting purposes, the use of transformers has been discouraged, to maintain both initial and operation costs at a minimum.

Furthermore, the presence of incandescent filaments introduces a factor of fragility in the system. When it is recalled that this filament, at each electrode, is essential in preparing the tube for starting, and when it is further recalled that after starting, the arc is maintained across these very same electrodes, then it will readily be appreciated that despite efforts made to shield these filaments, they are subjected to both ionic and electronic bombardment, and when

the arc settles on the filament, to detrimental vaporization as well. Thus, despite the increased longevity of these tubes, their life span is definitely limited. Additionally, inasmuch as these filamentary electrodes are oxide coated, to increase their electron emission, blackening of the tube walls occurs, due to deposit thereon of spent oxide material volatilized off the filaments.

Unstable operation at low temperatures limits the use of known tube lighting systems in outdoor use, or show window display use, to conditions where at least moderate temperatures prevail. Where the temperatures are low, or the tube is exposed to extreme cooling effects, such as winds or the like, the mercury tends to condense out, and the service voltage is found to be insufficient to maintain a steady arc in the rarefied atmospheres prevailing under such conditions. Somewhat similarly these known systems, operating at service voltages of from 120 up to 250 volts supply, are unable to operate at dimmer light outputs because with any appreciable decrease in impressed voltages, the peak voltage of the current supply will approximate or fall below the value at which an arc can be struck across the tubes. Experience shows that the arc extinguishes when the service voltage falls 25% below rated values.

In our application for patent Serial No. 402,410, filed of even date herewith, and entitled Luminescent tube system and apparatus, we have set forth novel means for avoiding in large measure the difficulties and disadvantages pointed out in the foregoing. To that end, we have described in that application a fluorescent tube lighting system in which the operational and maintenance costs are materially reduced below those hitherto current, which has a greater light output per unit of power input than was hitherto possible of achievement, in which the useful life of the tube is greatly increased, and which is capable of satisfactory dimming operation. However, no provision was made in the systems according to that application, for avoiding the detrimental flicker or stroboscopic effect. Our present invention is directed to the substantial decrease of that stroboscopic effect in systems according to our prior invention, and which employ our new high leakage reactance autotransformer for energizing the tube load, and also the production of a high leakage reactance autotransformer which will operate at high efficiencies while energizing such tube circuits. A further object of our invention is to produce a system of fluorescent tube lighting employing our new transformer, all as aforesaid, which system has high power factor, and which is capable of steady and satisfactory operation under cold weather conditions.

While in incandescent lighting operation on alternating current supply, of say 60 cycles, wherein the voltage rises and falls from zero to peak voltage and back again to zero some 120 times per second, the heat retentivity of the tungsten filament is such that the light emission persists during the momentary periods of no voltage, there is no such heat retentivity in the case of fluorescent gas discharge tubes; and even where the service mains are of as high as 60 cycles frequency, the arc strikes and extinguishes during each half cycle as the voltage rises and falls, first to the striking potential and then below the extinguishing potential. This phenomenon of alternate striking and extinguishing during each half-cycle of current flow gives rise to

a perceptible and objectionable flicker, known in the art as stroboscopic effect. Much attention has been directed by the workers in the art to the satisfactory elimination of this source of annoyance.

While the invention as set forth in our co-pending application presents an effective solution of many of the fluorescent tube lighting problems stated herein, nevertheless, while some

10 effort is made according to that application to correct the system power factor by the use of a large capacity condenser, without, however, disturbing the design of the transformer core to that end, we find that more effective use of the 15 power factor regulating condenser can be obtained if it be disposed asymmetrically of the transformer load system, in one branch of its double current secondary. When so disposed, the condenser not only fulfills its function of power factor regulation, but at the same time, produces 20 a phase unbalance in the double secondary circuits so that when one tube of a battery or bank of tubes is in its period of darkening when the arc is extinguished, the other tube will be energized and an arc struck thereacross.

25 The use of our high leakage reactance transformer as the power source interposes some interesting questions of design to ensure proper operation with high efficiency. The solution of 30 these problems, forming the subject matter of this application, involves many features of novelty, and accordingly, a further object of our invention is to produce a system of fluorescent tube lighting characterized by the minimizing of 35 detrimental flicker or stroboscopic effect, and having high system power factor, as well as to produce a new double circuit, high leakage reactance autotransformer capable of energizing such system at high efficiency while maintaining 40 the current flow thereacross within safe practical limits.

It will be recalled that, to prevent hysteresis loss, the iron core ballasts used in the conventional tube lighting systems have been constructed with cores which are formed of a number of iron laminations. In operation, however, these laminations give rise to a detrimental hum or chattering which has been found to make the use of such systems objectionable in places where 45 extreme quite ordinarily prevails, such for example, as in homes, libraries and the like.

For the same reasons as controlled in connection with the iron core ballasts, the core of our new transformer likewise is comprised of a large number of iron laminations. In the absence of 50 special precautions our new transformer, too, would therefore give rise to detrimental hum or chattering. An important object of our invention is thus seen to reside in the construction of a transformer which, when in operation, is substantially free from detrimental hum or chattering.

55 Referring now to the practice of our invention, attention is directed to Figure 1, in which there is illustrated a double-circuit high leakage reactance shell-type transformer, having parallel magnetic flux paths, and with its windings connected in autotransformer connection, which transformer is associated in novel circuit arrangement with fluorescent gas discharge tubes connected for cold cathode operation.

The transformer illustratively consists of a core frame, having a central leg 10, outer legs 11, 12, parallel and in spaced relation with, and arranged one on each side of central leg 10, and

end pieces 13, 13 and 14, 14 extending at right angles to said legs, and joining them at their respective ends. Mid core portions M1, M2 extend at right angles from outer legs 11, 12, respectively, towards central leg 10. In practice we prefer to form the legs which comprise core portions M1, M2 about .002 inch longer than the ends comprising end pieces 13 and 14, for reasons which will appear hereinafter.

As will be apparent from Figure 2, the transformer core is comprised, in conventional manner and to prevent hysteresis loss, of a large number of lamina 15, shown in the illustrations as being of greatly exaggerated width, for clarity. As has already been suggested these lamina, under the influence of rapidly alternating electromagnetic stress, give rise to a detrimental chattering—a chattering which is also experienced in conventional installations employing iron-core inductive ballasts as current-limiting means, and retarding to a certain extent the acceptance of fluorescent lighting systems in household lighting and in other locales where the prevailing quiet is such that the hum of the inductance is noticeable.

To avoid this chattering we provide silencing clamps transversely about the core, and serving to clamp the lamina firmly together. Preferably we provide such clamps at the mid-portions of the core legs 11 and 12 and at both ends of these core legs. Each of the clamps consists of two substantially U-shaped members 16, 17, each terminating at their free ends in outwardly extending tabs or wings 18, 19. These tabs are bored for the reception of a clamping screw 20. As shown, these clamping screws are each associated with a pressure-distributing washer 21 and a takeup nut 22. When the pair of U-shaped clamps are disposed in opposed relation about the lamina 15, and the screws 20 are tightened down, the clamps engage firmly about the lamina, and substantially all chatter or hum in the transformer core is eliminated, and perfect magnetic butt joints are achieved. Moreover, when clamping pressure is properly exerted, the magnetic reluctance per unit of bearing area is the same at both the mid-core portions and end pieces. It is also advantageous at times to employ C-shaped silencing clamps (not shown) at shunts Sh1, Sh2, Sh3 and Sh4.

Spaces for the reception of the transformer windings are formed in the core by the described association relative to each other of the outer and inner legs, the mid-core portions and the end pieces. These spaces, rectangular in shape, are disposed in pairs, one pair on each side of mid-core portions, and the spaces of each pair being disposed on opposite sides of said central leg. The primary coils and secondary coils are disposed in pairs about said central leg, one pair of coils in each said pair of spaces.

A primary coil and a secondary coil constituting each pair, are disposed about and link each parallel flux path. Primary coils P1, P2 are disposed adjacent mid-core portions M1, M2, one of each side thereof. Secondary coils S1 and S2 are disposed adjacent end pieces 14, 13 respectively. Primary coil P1 and secondary coil S1 are linked in magnetic circuit with each other, while primary coil P2 is linked in magnetic circuit with secondary coil S2.

An important feature of our transformer is its high leakage characteristics. To impart these desired characteristics, in each said magnetic

circuit, between each primary and its associated secondary, intermediate magnetic shunts Sh1, Sh2, Sh3, Sh4 extend towards but short of central leg 10, thus providing corresponding air-gaps G1, G2, G3, G4 of magnetic reluctance calibrated in accordance with the load for which the transformer is adapted. Shunts Sh1, Sh2 and air-gaps G1, G2 are associated with primary coil P1 and secondary coil S1, while shunts Sh3, Sh4 and air-gaps G3, G4 are associated with primary coil P2 and secondary coil S2. The function of these intermediate shunts will be developed at a later point herein.

The primary coils P1, P2 are connected across a source of electrical supply 23, which preferably is an ordinary alternating-current service line. While the primary coils may be parallel or series-connected across this service, in aiding or opposed relation, we prefer to connect them in parallel-opposed relationship, for reasons which will develop. Thus terminal 24 of primary coil P1 is connected through leads 25, 26 and 27 to left-hand side of source 23. Similarly, terminal 28 of primary coil P1 is connected through leads 29, 30 to right-hand side of source.

In like manner, terminal 31 of primary coil P2 is connected through leads 32, 33 to the right-hand side of source 23, while terminal 34 of the primary coil is connected through lead 27 to the left-hand side of the source.

For a given half-cycle of the alternating-current supply, current flows from the right-hand side of source 23, through leads 30, 29 to terminal 28, thence to the left (in Figure 1) through primary coil P1, terminal 24, and thence through leads 25, 26, 27 back to the left-hand side of the source. Simultaneously a parallel circuit may be traced from the right-hand side of source 23 through leads 33 and 32 to terminal 31, thence to the right (in Figure 1) through primary coil P2, terminal 34, and thence through lead 27 back to the left-hand side of the source. During alternate half-cycles of the current supply the direction of current flow through the two parallel paths is of course just the reverse of those just traced. It will be observed that the primary coils are in bucking relation, so that the flux produced thereby tends to flow in opposite directions. This means that the principal body of flux courses the mid-core portions M1, M2, so that they must be designed to serve as conduits for the flux, without saturation effects.

By connecting the primary coils P1, P2 in parallel across the source 23, the full supply potential is impressed across their windings. Where series connection of the primary coils across the energy source prevails, however, each primary coil receives only its share of the total potential output of the supply source. For a given operating voltage, the number of turns in two parallel connected primary windings must be double the number in two series connected primaries in order to maintain a constant volt per turn relationship. Thus, where a transformer core of particular cross-section is employed and a constant flux density is desired, the number of turns in the primary coil sections must be altered when the particular manner in which the coil sections are connected is changed.

We prefer to connect each secondary coil electrically in series across the network consisting of the two parallel opposed primary coils. With the tubes in series circuit with their corresponding secondary coils, then with the electrical circuits as described, upon the arc across either

tube striking, increased current flows through the associated secondary coil. Thus current necessarily courses the network electrically connected therewith, and splits thereacross in accordance with the relative impedance of the branches of that network. Since the impedance of the branch including the primary coil magnetically linked with the energized secondary coil increases materially in response to such energization, however, only a small part of this current flows through that branch. By far the larger part flows through the other branch, including the primary coil linked with the other magnetic circuit. Consequently, an increased quantity of flux is generated in this other magnetic path, so that increased voltage is induced in the associated secondary coil. This increased potential, impressed across the terminals of the tube in circuit with that secondary coil, ensures positive striking of arc across that tube.

Thus a circuit may be traced from secondary coil S1, terminal 35, through conductor 30, to junction 29'. The other leg of this circuit includes terminal 38 of the secondary coil, lead 37, tube T1, and lead 36, to junction 25'. At junctions 29' and 25' the secondary coil circuit is connected across the primary coil network. One branch may be traced from junction 29', lead 29, terminal 28, to the left in Figure 1 across primary coil P1, terminal 24, and lead 25 to junction 25'. The other branch may be traced from junction 29', leads 30, 33, 32, terminal 31, to the right in Figure 1 through primary coil P2, terminal 34, leads 27 and 26, back to junction 25'. During the next half-cycle, of course, the direction of current flow is just the reverse of that described.

Since electrical disturbances are produced in tube T1 due to electrical discharges across the gas and mercury vapor filling thereof, and since due to the autotransformer connections, primary coil P2 is in circuit therewith, any disturbance in tube T1 will be carried into the primary circuit. To eliminate this detrimental source of annoying radio disturbance, condenser C1 is connected across the tube to trap the high-frequency oscillations which otherwise would reach the primary circuit. Since condenser C1 need have only a small capacity, say about .005 microfarad, and consequently has a high capacitative reactance, it consumes but little energy, and does not in any way interfere with tube starting. Condenser C1 has no effect on the normal operation of the transformer.

Similarly, secondary coil S2 is electrically connected across the same primary coil network. Circuit may be traced as follows: From terminal 39 of secondary coil S2, lead 40, across condenser 41, tube T2, and lead 42 to junction 33'. The other leg of this circuit includes terminal 44 of secondary coil S2, and leads 43 and 26 to junction 26'. The current flows through one parallel branch from junction 33' up through lead 32, terminal 31 to the right in Figure 1 through primary coil P2, terminal 34, lead 27 to junction 26'. The other branch can be traced from terminal 33', leads 33, 30 and 29, terminal 28, to the left in Figure 1 through primary coil P1, terminal 24, and leads 25 and 26 back to junction 26'. In the next half-cycle, of course, the direction of current flow is the reverse of that described.

A large part of the foregoing, with the exception of the silencing clamps, has already been set forth in our said co-pending application, and

does not per se form part of this invention. The novelty herein resides in large measure in the production of a high leakage reactance transformer capable of satisfactory operation with a large capacity condenser disposed in one secondary circuit which results in power-factor correction with substantial minimizing of stroboscopic flicker, while maintaining high system and transformer efficiency.

Condenser 41 serves the dual function of correcting system power factor, and due to its asymmetrical location in one branch of the secondary circuits, produces a phase unbalance so that the arc discharges across the two tubes are out of phase with each other. This minimizes flicker, or what is known as stroboscopic effect, in batteries of two or more lamps.

Condenser 41 is necessarily of considerable size to introduce such balancing impedance. Its capacity is comparatively large even though it is placed in the high voltage secondary side of the transformer. Because primary coil P1 is connected in series with the condensive branch of the secondary, it has imposed on it not only the 60 cycle frequency of the service mains, but the superposed frequency of the condensive secondary circuit. Thus primary coil P1 must be wound of larger size wire to handle the larger current resulting therefrom.

The high impedance of the condenser 41 tends to resist the coursing of flux through leg 10 and interlinking secondary coil S2. Shunts Sh3 and Sh4 accordingly must be designed to have reluctance such that when the arc across tube T2 is struck, they will at that time by-pass the greater part of the primary flux coursing that magnetic circuit, their design is such that a quantity of primary flux sufficient to induce the required potential in secondary, coil S2 will still interlink that coil. This requirement necessitates designing shunts Sh3 and Sh4 of higher reluctance than shunts Sh1 and Sh2, for if they had an admittance as high as those two shunts, they would by-pass practically all the primary flux around coil S2, leaving the latter practically deenergized. Accordingly, shunts Sh3 and Sh4 are shorter than shunts Sh1 and Sh2, while air-gaps G3 and G4 are wider than air-gaps G1 and G2.

It is to be noted that since secondary coil section S2 has a leading current, the counterelectromotive force generated therein is not in phase with that of secondary coil S1. Moreover, the effective value of the primary flux in the condensive branch of the transformer remains higher than in the inductive branch. It follows from this that the primary coil P2 is not required to supply as much flux as does primary coil P1. Advantage is taken of this fact to reduce the size of the transformer by reducing the size of the wire constituting primary coil P2.

It is advantageous at this time to consider the manner in which the flux courses the several magnetic circuits of the transformer, and to consider how the leakage reactance of the transformer serves to limit the current flow through the fluorescent tube load.

Because of the leading current of the capacitative branch, flux is first generated in primary section P2. Choosing the path of least resistance, the flux may be considered as coursing to the right in Figure 1, and splitting into two substantially equal streams (because of the substantially equal physical and magnetic characteristics of the two paths) passes in the direction of the arrows. One part passes up through core por-

tion M_1 , to the left along leg 11 , down through end piece 13 , and the other part passes down through M_2 to the left along leg 12 , up through end piece 13 and there reunites with the flux from the other path at central leg 10 . The re-united flux travels to the right across leg 10 back to M_1 and M_2 thereby linking P_2 and S_2 . Potential is induced in secondary coil S_2 , which potential is impressed across the terminals of tube T_2 . Approximately 90 electrical degrees later, flux starts to flow from primary coil P_1 , and passing in the direction of the arrows, courses to the left along leg 10 . Bucking flux from the condensive branch of the transformer for the first 90 electrical degrees, the flux, choosing the path of least reluctance, branches and flows in substantially equal streams, one stream through core portion M_1 , to the right along leg 11 , down through end piece 14 , and reuniting with the other stream of flux in leg 10 , courses back to primary coil P_1 , traversing secondary coil S_1 . Meantime the other stream courses down through core portion M_2 , to the right along leg 12 , up through end piece 14 , and joining the other stream at leg 10 , courses back to primary P_1 .

One of the lamp circuits, usually the condensive branch of the secondary circuit containing lamp T_2 , may be expected to have an impedance sufficiently lower than the other to strike first, after the passage of but a few current cycles, assuming now a 440-volt supply.

Upon establishment of an arc across the tube, a high current flows through secondary S_2 . Consequently, this current flows through the primary network, electrically connected therewith. Since impedance builds up in primary coil P_2 simultaneously with arcing of tube T_2 , because coils P_2 and S_2 are in the same magnetic path, it is the smaller part of this current which flows through coil P_2 . The larger quantity flows through coil P_1 , still of low impedance, and induces a larger quantity of flux in the second magnetic path, which flux, interlinking coil S_1 , induces a higher voltage therein. Tube T_1 thus strikes more positively upon application of this high voltage across its terminals.

Of course, in alternate half-cycles of the energizing current, the direction in which the flux courses is the reverse of that just described. All in all, the time consumed from the closing of the switch across the service mains until both tubes are energized is a matter of but a few current cycles, as contrasted to the some 4 to 6 seconds or more as has been the case with the systems currently in use.

As soon as both tubes are energized, steady current flow conditions maintain. The intermediate shunts Sh_3 — Sh_4 , formerly paths of high reluctance, are now, due to the build-up of back magnetomotive force generated by secondary coils S_1 , S_2 , the paths of least reluctance. In fact, so great is the impedance in coil section S_2 due to condenser 41 , that were not the air-gaps G_3 and G_4 so designed as to provide sufficient reluctance, they would by-pass practically all the flux around the secondary coil S_2 , and would render the latter practically inactive. An important feature of our present invention accordingly, is the design of these air-gaps so that they are made much larger than the air-gaps G_1 , G_2 . These air-gaps G_3 — G_4 are calibrated so as to produce nearly unity power factor, in conjunction with condenser 41 .

The flow of larger currents through secondary coil S_2 and tube T_2 makes it necessary, as

pointed out hereinbefore, to provide primary coil P_1 of considerably larger gauge wire than that constituting primary coil P_2 .

More specifically, with steady flow conditions maintaining, flux flows to the right from primary coil P_2 , splits into two substantially equal and parallel streams and courses one stream up through core portion M_1 , thence to the left along leg 11 . A small amount of flux continues, coursing through secondary S_2 . To induce just the necessary voltage to maintain tube T_2 energized, however, the greater quantity flows down through shunt Sh_3 , across air-gap G_3 to leg 10 . The other stream flows down through core portion M_2 , thence to the left along leg 12 , from whence the greater part flows up shunt Sh_4 across air-gap G_4 . The two streams of flux reuniting at leg 10 , they flow back to the right along this leg, to primary coil P_2 . A half-cycle later the direction of flow of these flux streams is reversed.

About 90 electrical degrees out of phase with the streams of flux just traced, the flux coursing from primary coil P_1 passes to the left in Figure 1, and splitting at core portions M_1 , M_2 , passes one stream up and to the right along leg 11 , whence the greater part courses down across shunt Sh_1 and air-gap G_1 , and the other stream down and to the right along leg 12 , whence the greater part courses up across shunt Sh_2 and air-gap G_2 . All the flux reuniting at leg 10 , including that part just sufficient to induce in secondary coil S_1 the voltage necessary to energize the tube T_1 , courses as a single stream to the left in Figure 1, back to primary coil P_1 . A half cycle later the direction of coursing of the flux is reversed.

The presence of the condenser 41 results in an increase in the voltage in the condensive circuit. Accordingly, to produce the same open circuit voltage in both secondaries, we find it advantageous to form coil S_2 with a few less turns of wire than coil S_1 . In our 100 watt unit, for example, this difference in potential is found to be 35 volts.

Another embodiment of our electrical system is illustrated in Figure 3. Since the core employed in connection with the embodiment now to be described is much like to that employed in the embodiment first-described, its description has been omitted from the illustration of Figure 3.

In this new embodiment, primary coils P_1 , P_2 and secondary coils S_1 , S_2 are provided, primary and secondary coils P_1 , S_1 and P_2 , S_2 , being paired in separate parallel magnetic circuits. Primary coils P_1 , P_2 are connected together in series-opposed relationship across a source of alternating current supply 23 , the winding of primary coil P_1 being wound in a direction reverse to that of the winding of coil P_2 . Secondary coils S_1 , S_2 are associated in autotransformer connection across the primary coils P_1 , P_2 , and to avoid the necessity of a large number of turns in the secondary coils to produce rated secondary voltages since the primary coils are series connected, each secondary coil is in separate series circuit with both primary coils. Thus secondary coil S_1 , for example, is electrically series connected through conductor 45 , first with primary coil P_2 in the opposite magnetic circuit, thence by lead 46 to tube T_1 , and through lead 47 back to the secondary coil. Similarly, and in separate secondary circuit, an electrical series-circuit may be traced from secondary coil S_2 through lead 48 , across condenser 49 , first to the

primary coil P1 in the opposite magnetic circuit, thence through lead 45 to tube T2, through lead 50, back to the secondary coil. If desired, a high resistance R can be provided about condenser 49; to bring about slow discharge of the condenser, after circuit operation and thus prevent electrical shock.

Just as in the first embodiment, the condensive branch of the secondary has a leading current. The increased current flow from the 60 cycle induced supply plus the impressed harmonics from the condenser action requires the primary coil P1 to be wound of larger size wire.

Because of the impedance interposed by the condenser 49, the back magnetomotive force generated by coil S2 is so great that without proper design of shunts Sh3, Sh4 (Figure 1), practically all the flux would be shunted through the paths comprising these shunts and their associated air-gaps G3 and G4, around coil S2, leaving the latter de-energized. We purposely, therefore, increase the width of air-gaps G3, G4, and hence the reluctance of the shunts of which they form part, to an extent that even after energization of the load across secondary coil S2, and the consequent generation of back magnetomotive force from that coil, enough primary flux interlinks that coil to impress required operating potential across the secondary load.

The condenser 49 produces a condition of phase unbalance in the two secondary circuits, so that one of tubes T1, T2, remains energized while the arc is extinguished in the other tube. By consequence, tube flicker is reduced to a minimum, and no longer constitutes a source of annoyance. Because of the out of phase coursing of the two streams of primary flux from the primary coils P1, P2, we find that there is less weakening of the primary flux in the condensive side of the transformer, so that the primary coil P2 can be wound of a smaller size wire.

In this embodiment let us assume a half-cycle of charging current flow such that flux is developed by primary coil P1 in the direction according to the arrows in Figure 1. Then the flux, passing to the left in coil P1 along leg 10, bucks the flux streaming in the opposite direction from primary coil P2. The stream from coil P1 splits into two branches. One branch courses up mid core portion M1 and to the right along leg 11. Only a small part courses down the high reluctance shunts Sh1. The greater parts of it courses down first end piece 14, to the right hand end of leg 10. At the same time, the other branch of flux from coil P1 courses down mid core portion M2 and to the right along leg 12. Only a very small part of the flux courses across the high reluctance shunt Sh2. By far the greater part moves up second end piece 14 to the right hand end of central leg 10. The two branches of the stream of primary flux reuniting at leg 10, the combined stream now courses to the left along leg 10, back to the primary coil P1. During its passage, it interlinks secondary coil S1 and induces a high potential therein.

In the meantime, flux from primary coil P2, which as indicated by the arrows, flows in a direction opposite from the flux in coil P1, courses to the right in Figure 1 along central leg 10. Here the stream splits, and one branch courses up mid core portion M1 and to the left along leg 11. Only a small part of the flux courses across high reluctance shunt Sh3. The greater part

courses down first end piece 13, to the lefthand end of central leg 10. Meanwhile, the other branch courses down core portion M2 and to the left along leg 12. Only a small part of this flux courses across high reluctance shunt Sh4. The greater part courses up second end piece 13. The two branches reunite at leg 10. The combined stream then courses back to primary coil P2. During its passage it interlinks secondary coil P2 and generates a high voltage therein.

During the next adjacent half-cycle, the direction of the magnetic flux of course is reversed. It will be sufficient for purposes of illustration, to describe the reverse coursing of flux at this time, for but a single one of the two parallel magnetic paths. Confining our attention, therefore, to the magnetic path about which are disposed coils P1 and S1, coursing of the magnetic flux will be observed to be in a direction opposite to that indicated by the arrows in Figure 1. The flux from coil P1 courses to the right along leg 10, and only a small part of it branches across shunts Sh1 and Sh2, the greater part interlinking secondary splits into two branches. One branch courses up end piece 14 and to the left along leg 11. It is joined by the small quantity of flux which courses shunt Sh1. This branch courses down core portion M1 to central leg 10 and back to coil P1. The other branch courses down second end piece 14 and to the left along leg 12. It is joined by that path of the flux which courses shunt Sh2. This branch courses up core portion M2, to central leg 10 and back to coil P1.

The circuit for one of these tubes, usually for tube T2, will be found to have a lower impedance than the other tube circuit. After several reversals of the secondary current, therefore, the voltage impressed across the terminals of the tubes, excites the gas contents thereof to such a degree of excitation that the arc strikes across the tube. As soon as that happens, a large current begins to flow in the related secondary coil S2. Since coil S2 is electrically in circuit with primary coil P1 and P2, this same current flows through these two coils. Furthermore, since the primary flux depends on the ampere turns in the primary coils, this increased current flow induces increased primary flux. This increase of flux in the second parallel magnetic paths, including secondary coil S1, results in increase in the potential induced in that coil. The elevated potential impressed across tube T1 causes more positive striking of the arc thereacross.

The high impedance which the secondary coil S2 now has, causes by far the greater part of flux from primary coil P2 to shunt along high reluctance shunts Sh3 and Sh4 and their associated air-gaps G3, G4, in large measure by-passing secondary coil S2. The design of the shunts is such that only sufficient flux now interlinks secondary coil S2 to induce therein voltage high enough to maintain arc discharge across tube T2.

Shortly after the arc strikes across tube T2, tube T1 likewise becomes energized. These tubes then operate under steady current conditions, and both coils S1 and S2 are of relatively high impedance. The secondary flux developed therein opposes the primary flux, and in each parallel magnetic path, the greater part of the primary flux now seeks the high reluctance shunt paths, which are now of lesser reluctance than are the paths interlinking the secondary coils.

We are enabled, by use of the system and transformer described, to operate banks of fluorescent gas discharge tubes at high system pow-

er-factor in the substantial absence of detrimental flicker or stroboscopic effect in the light emission from the tubes. At the same time, by our novel design of the transformer, we are enabled to employ a high leakage reactance type of autotransformer for energizing the system, with all of its attendant advantages of sturdiness, simplicity, compactness, low operating costs, and elimination of delicate and complicated auxiliaries, while maintaining transformer efficiency at an optimum value.

We claim:

1. An electrical system for energizing a plurality of fluorescent gas discharge tubes at high system power-factor and with stroboscopic effect reduced to a minimum, comprising a high leakage reactance transformer having a magnetic core and a primary winding and a plurality of secondary windings linking the same; a source of electrical energy across which said primary winding is connected; and a fluorescent gas discharge tube connected in circuit with each secondary winding and a power-factor regulating condenser in series circuit with one said secondary winding, the said transformer core including high leakage reactance shunts magnetically between primary and secondary windings for by-passing magnetic flux around the associated secondary winding when the load on the latter increases, the reluctance of said shunts in each magnetic circuit being calibrated to provide more reluctance in that magnetic circuit which energizes the condenser.

2. A fluorescent tube lighting system for operation at high power-factor and with tube flicker minimized, comprising a high leakage reactance transformer having a core and a primary winding and a plurality of secondary windings linking said core; a fluorescent gas discharge tube connected in circuit with each secondary winding; and a power-factor regulating condenser in series circuit with one said secondary winding, said transformer core including high leakage reactance shunts between the primary winding and the secondary windings, the reluctance of said shunts being calibrated to provide more reluctance in that magnetic circuit which energizes the condenser, the secondary winding in said last-mentioned magnetic circuit being comprised of such fewer number of turns of wire as compared to the other secondary winding that its open-circuit voltage will be the same as that of the other secondary winding.

3. A fluorescent tube lighting system for operation at high power-factor and with tube flicker minimized, comprising a high leakage reactance autotransformer having double magnetic circuits employing a common core leg, a primary coil and a secondary coil linking each magnetic circuit with the primary coil disposed adjacent said common leg, the primary and secondary coils being associated in autotransformer connection; a fluorescent gas discharge tube in circuit with each secondary coil; and a power-factor regulating condenser in series circuit with one said secondary coil, said transformer magnetic circuits including high leakage reactance shunts in each magnetic circuit between magnetically paired primary and secondary coils, the reluctance of said shunts in each magnetic circuit being calibrated to provide more reluctance in that magnetic circuit which energizes the condenser, the primary coil in said last-mentioned magnetic circuit being wound of small size wire to provide the lessened quantity of primary flux required to

energize the condenser branch of the transformer secondary, while the primary coil in the other magnetic circuit is wound of comparatively larger size wire, to provide the increased magnetic flux required to energize the inductive branch of the transformer secondary.

5. An electrical system for energizing batteries of fluorescent gas discharge tubes of high system power-factor with stroboscopic effect minimized, comprising a high leakage reactance autotransformer having double magnetic circuits, a primary coil and a secondary coil in each said magnetic circuit; a source of electrical energy across which said primary coils are energized in parallel-opposed connection, each said secondary coil being electrically connected across the network consisting of the parallel-connected primary coil; a fluorescent gas discharge tube in circuit with each secondary coil; and a power-factor regulating condenser in series circuit with one said secondary coil, said autotransformer including high leakage reactance shunts in each magnetic circuit between magnetically paired primary and secondary coils, the reluctance of said shunts in each magnetic circuit being calibrated to provide more reluctance in that magnetic circuit which energizes the condenser, the opposed connection of the primary coils, and the electrical connection of the secondary coils across the network of primary coils, ensuring high flux in the other magnetic circuit upon increase of the load energized by one said magnetic circuit.

10. An electrical system for energizing batteries of fluorescent gas discharge tube of high system power-factor with stroboscopic effect minimized, comprising a high leakage reactance autotransformer having double magnetic circuits, a primary coil and a secondary coil in each said magnetic circuit, each said secondary coil being electrically series-connected first with the primary coil in the opposite magnetic circuit, and then with the primary coil in its own magnetic circuit; a source of electrical energy across which said primary coils are energized in series-opposed connection; a fluorescent gas discharge tube in circuit with each secondary coil; and a power-factor regulating condenser in series circuit with one said secondary coil, said autotransformer including high leakage reactance shunts in each 15 magnetic circuit between magnetically paired primary and secondary coils, the reluctance of said shunts being calibrated to provide more reluctance in that magnetic circuit which energizes the condenser; the opposed connection of the secondary coils with the primary coils and the electrical connection of the secondary coils with the primary coils in the opposite magnetic circuit ensuring high flux in the other magnetic circuit upon increase of the load energized by one said magnetic circuit.

15. An electrical system for energizing batteries of fluorescent gas discharge tubes of high system power-factor with stroboscopic effect minimized, comprising a high leakage reactance autotransformer having double magnetic circuits, a primary coil and a secondary coil in each said magnetic circuit, each said secondary coil being electrically series-connected first with the primary coil in the opposite magnetic circuit, and then with the primary coil in its own magnetic circuit; a source of electrical energy across which said primary coils are energized in series-opposed connection; a fluorescent gas discharge tube in circuit with each secondary coil; and a power-factor regulating condenser in series circuit with one said secondary coil, said autotransformer including high leakage reactance shunts in each 20 magnetic circuit between magnetically paired primary and secondary coils, the reluctance of said shunts being calibrated to provide more reluctance in that magnetic circuit which energizes the condenser, the opposed connection of the primary coils, and the electrical connection of the secondary coils across the network of primary coils, ensuring high flux in the other magnetic circuit upon increase of the load energized by one said magnetic circuit.

25. An electrical system for energizing batteries of fluorescent gas discharge tube of high system power-factor with stroboscopic effect minimized, comprising a high leakage reactance autotransformer having double magnetic circuits, a primary coil and a secondary coil in each said magnetic circuit, each said secondary coil being electrically series-connected first with the primary coil in the opposite magnetic circuit, and then with the primary coil in its own magnetic circuit; a source of electrical energy across which said primary coils are energized in series-opposed connection; a fluorescent gas discharge tube in circuit with each secondary coil; and a power-factor regulating condenser in series circuit with one said secondary coil, said autotransformer including high leakage reactance shunts in each 30 magnetic circuit between magnetically paired primary and secondary coils, the reluctance of said shunts being calibrated to provide more reluctance in that magnetic circuit which energizes the condenser; the opposed connection of the secondary coils with the primary coils and the electrical connection of the secondary coils with the primary coils in the opposite magnetic circuit ensuring high flux in the other magnetic circuit upon increase of the load energized by one said magnetic circuit.

35. An electrical system for energizing batteries of fluorescent gas discharge tube of high system power-factor with stroboscopic effect minimized, comprising a high leakage reactance autotransformer having double magnetic circuits, a primary coil and a secondary coil in each said magnetic circuit, each said secondary coil being electrically series-connected first with the primary coil in the opposite magnetic circuit, and then with the primary coil in its own magnetic circuit; a source of electrical energy across which said primary coils are energized in series-opposed connection; a fluorescent gas discharge tube in circuit with each secondary coil; and a power-factor regulating condenser in series circuit with one said secondary coil, said autotransformer including high leakage reactance shunts in each 40 magnetic circuit between magnetically paired primary and secondary coils, the reluctance of said shunts being calibrated to provide more reluctance in that magnetic circuit which energizes the condenser; the opposed connection of the primary coils, and the electrical connection of the secondary coils across the network of primary coils, ensuring high flux in the other magnetic circuit upon increase of the load energized by one said magnetic circuit.

45. An electrical system for energizing batteries of fluorescent gas discharge tube of high system power-factor with stroboscopic effect minimized, comprising a high leakage reactance autotransformer having double magnetic circuits, a primary coil and a secondary coil in each said magnetic circuit, each said secondary coil being electrically series-connected first with the primary coil in the opposite magnetic circuit, and then with the primary coil in its own magnetic circuit; a source of electrical energy across which said primary coils are energized in series-opposed connection; a fluorescent gas discharge tube in circuit with each secondary coil; and a power-factor regulating condenser in series circuit with one said secondary coil, said autotransformer including high leakage reactance shunts in each 50 magnetic circuit between magnetically paired primary and secondary coils, the reluctance of said shunts being calibrated to provide more reluctance in that magnetic circuit which energizes the condenser; the opposed connection of the secondary coils with the primary coils and the electrical connection of the secondary coils with the primary coils in the opposite magnetic circuit ensuring high flux in the other magnetic circuit upon increase of the load energized by one said magnetic circuit.

55. An electrical system for energizing batteries of fluorescent gas discharge tube of high system power-factor with stroboscopic effect minimized, comprising a high leakage reactance autotransformer having double magnetic circuits, a primary coil and a secondary coil in each said magnetic circuit, each said secondary coil being electrically series-connected first with the primary coil in the opposite magnetic circuit, and then with the primary coil in its own magnetic circuit; a source of electrical energy across which said primary coils are energized in series-opposed connection; a fluorescent gas discharge tube in circuit with each secondary coil; and a power-factor regulating condenser in series circuit with one said secondary coil, said autotransformer including high leakage reactance shunts in each 60 magnetic circuit between magnetically paired primary and secondary coils, the reluctance of said shunts being calibrated to provide more reluctance in that magnetic circuit which energizes the condenser; the opposed connection of the primary coils, and the electrical connection of the secondary coils across the network of primary coils, ensuring high flux in the other magnetic circuit upon increase of the load energized by one said magnetic circuit.

60. A luminescent tube lighting system comprising in combination, a high leakage reactance transformer having a magnetic core and a primary winding and a plurality of secondary windings mounted thereon, a corresponding plurality of luminescent tube loads individually connected to said secondary windings, and condenser means connected in series with one of said tube loads and its associated secondary winding to limit the current therein, said transformer having core shunt means associated with another of said secondary windings to provide a magnetic shunt path around the same of substantially lower reluctance than any magnetic leakage path around the first-mentioned secondary winding in order

to limit the current in the tube load to which the second-mentioned secondary winding is connected.

7. A luminescent tube lighting system comprising in combination, an autotransformer having a magnetic core and a primary winding and two secondary windings mounted thereon with the primary winding connected in autotransformer relation with at least one of said secondary windings, two luminescent tube loads individually connected to the two secondary windings, and a condenser connected in series with one tube and the secondary winding to which it is connected to limit the current in that tube, the said transformer having a core shunt to provide a magnetic path around the other secondary winding of lower reluctance than the leakage path around the first secondary winding in order to limit the current in the other tube.

8. A fluorescent tube lighting system, comprising a high leakage reactance transformer including parallel magnetic paths having a leg in common, a primary coil and a secondary coil linking each of said paths, the primary coils being disposed adjacent and on opposite sides of said common leg, each magnetic path including magnetic shunts wherein the magnetic reluctance of one is substantially less than that of the other; a fluorescent gas discharge tube connected in circuit with each of said secondary coils; and a condenser disposed in circuit with at least the one of said tubes connected to the secondary coil associated with the shunt of greater reluctance.

9. A luminescent tube lighting system comprising in combination, a shell-type transformer having a core with a central leg and two outside legs, a primary winding and two secondary windings mounted on said central leg with the primary being disposed between the secondary windings; a pair of luminescent tubes connected to said transformer, one being connected to one secondary winding and the other being connected to the other secondary winding; and a condenser connected in series with one tube and the secondary winding to which the same is connected, said transformer including a shunt core path from said central core leg to the outside core legs at a point between the other secondary winding and the primary winding of substantially lower reluctance than any shunt path be- 40

50 tween the first-mentioned secondary winding and the primary winding.

10. A luminescent tube lighting system comprising in combination, a transformer having a magnetic core with a primary winding and two secondary windings mounted thereon, two luminescent tube loads in parallel spaced relation individually connected to said secondary windings, two condensers individually connected in parallel with said two tubes, and a condenser connected in series with one secondary winding, said transformer having core shunt means to provide a shunt path between the other secondary winding and the primary of lower reluctance than any shunt path between the first-mentioned secondary winding and the primary winding.

11. In combination, a transformer having a core and a primary winding and two secondary coil sections mounted on said core, two luminescent tubes individually connected across the terminals of individual secondary coil sections, and a condenser connected in series with one of said tubes and its associated secondary coil section, said condenser being of sufficient capacity to substantially limit the current in said one tube and coil section, said transformer core having magnetic core shunt means around the other of said secondary coil sections for limiting the current in that coil section and its associated tube, said shunt means providing a shunt path of substantially lower reluctance than any shunt path around the secondary coil section connected to said condenser.

12. In a luminescent tube lighting system, the combination of a transformer of the shell type having a primary and plurality of secondary coil sections mounted on a central core leg, a plurality of luminescent tube loads individually connected to individual secondary coil sections, condenser means included in the circuit of at least one of said tube loads and secondary coil sections and for reducing stroboscopic effect of the tube loads, and magnetic core shunt means around at least one other of said secondary coil sections for limiting the current therein, said core shunt means being of substantially lower reluctance than any shunt path around the secondary coil section connected to said condenser means.
